(57) **CLAIM**

The ornamental design for a slide-lock lid, as shown and described.

DESCRIPTION

FIG. 1 is a front isometric view of a slide-lock lid in a closed position according to our new design.

FIG. 2 is a first side isometric view thereof.

FIG. 3 is a second side isometric view thereof.

FIG. 4 is a front side elevation view thereof.

FIG. 5 is a second side elevation view thereof.

FIG. 6 is a top plan view thereof.

FIG. 7 is a front isometric view of the slide-lock lid in an open position.

FIG. 8 is a first side isometric view thereof.

FIG. 9 is a second side isometric view thereof.

FIG. 10 is a first side elevation view thereof.

FIG. 11 is a second side elevation view thereof; and,

FIG. 12 is a top plan view thereof.

The shade lines in the Figures show contour and not surface ornamentation. The broken lines show portions of the article and environment that form no part of the claimed design.

1 Claim, 6 Drawing Sheets
